CRYSTAL NOVELTY AND PAPERWEIGHT

William M. Snyder, Covington, Tenn., assignor to
Sarah S. Snyder, Covington, Tenn.Original application October 8, 1943, Serial No.
505,515. Divided and this application January
7, 1948, Serial No. 873

3 Claims. (Cl. 41—10)

1

My invention relates broadly to crystal novelties and more particularly to an improved structural arrangement for mounting a figure within a fluid container for facilitating production and improving the circulation of fluid and precipitate therein for simulating whirling snow about the figure.

One of the objects of my invention is to provide a structural arrangement for mounting a figure within a liquid filled container where the figure and base thereof are substantially spaced from the interior of the container to facilitate circulation of liquid and suspended precipitate within the container and improving the simulating of whirling snow.

Another object of my invention is to provide an arrangement of recesses or pockets in the interior walls of the neck of a container with radially extending lugs formed on the figure and fitting within the pockets or recesses for supporting the figure in spaced relation to the interior walls of the container for allowing substantially unobstructed circulation of fluid about the figure.

Still another object of my invention is to provide a construction of support for a figure within a liquid filled container wherein the interior of the neck of the container and the base of the figure are mutually shaped to permit both rigid support of the figure and circulation of fluid about the figure within the container.

A further object of my invention is to provide a construction of figure enclosed container and coacting figure in which the figure is provided with a frusto-conical base coacting with a frusto-conical shaped internal neck of the container in such spacial relation thereto as will allow circulation of the fluid and floatingly suspend precipitate freely about the figure.

A still further object of my invention is to improve the structure of support for a figure within a fluid container and facilitate the circulation of fluid about the figure by forming circulatory passages for the fluid through the figure or around the base thereof to permit a whirling action of precipitate within the fluid simulating falling snow.

Another object of my invention is to provide an arrangement of crystal novelty including a fluid submerged figure where the figure is provided with channelways extending either longitudinally or transversely of the container or both for facilitating circulation of fluid with suspended precipitate therein for thereby simulating the action of whirling snow.

2

Still another object of my invention is to provide a construction of crystal novelty in which a container is provided with a neck portion at one side thereof, the interior core of which is corrugated for supporting on the peaks of the corrugations a frusto-conical base of an ornamental figure providing spaced passageways for the circulation of fluid around the figure for establishing fluid currents which produce a whirling action on floatingly suspended particles therein simulating snow.

Other and further objects of my invention reside in a construction of crystal novelty designed for mass production on an inexpensive basis as set forth more fully in the following specification by reference to the accompanying drawings, in which:

Figure 1 is a vertical sectional view taken through the crystal novelty and paperweight of my invention and illustrating the coaction of the corrugated neck of the container and the frusto-conical shaped base of the ornamental figure within the container; Fig. 2 is a vertical sectional view taken substantially on line 2—2 of Fig. 1; Fig. 3 is a horizontal sectional view taken substantially on line 3—3 of Fig. 1; Fig. 4 is a transverse sectional view taken substantially on line 4—4 of Fig. 1; Fig. 5 is a fragmentary sectional view showing the neck of the container and the corrugations provided therein; Fig. 6 is a fragmentary elevational view of the frusto-conical base of the ornamental figure employed in the assembly of Figs. 1—4; and Fig. 7 is a horizontal sectional view taken substantially on line 7—7 of Fig. 6.

My invention is directed to a construction of crystal novelty of the general type set forth in my copending application Serial No. 505,515, filed October 8, 1943, now Patent No. 2,435,612 of February 10, 1948. In my present invention I have provided means for positively supporting the figure within the container in spaced relation to the walls of the container with paths so arranged that circulation of the liquid within the container and movement of the precipitate suspended in the liquid may be facilitated. I provide pockets or recesses in the interior surface of the neck of the container for receiving lugs which extend from the figure which is inserted into the container. The figure is thus positively spaced from the interior of the container permitting free circulation of the fluid and precipitate suspended in the fluid for simulating whirling snow. The base of the figure is frusto-conical, conforming with the shape of the

interior of the neck of the container and spaced therefrom to allow circulation of the fluid. Passages may be provided through the base of the figure for facilitating circulation for thereby improving the simulated whirling snow resulting from the agitation of the precipitate in the fluid. Various shapes may be imparted to the base of the figure complementary to the internal shape of the neck of the container for securing the figure in position while permitting circulation of the precipitate within the fluid. The figure may be of solid construction as well as of hollow construction with provision made for the passage of the circulating fluid through the base of the figure. Various constructions of closure caps may be employed as set forth more fully in my copending application Serial No. 505,515, filed October 8, 1943, *supra*.

Referring to the drawings in detail, reference character 1 designates the glass container of the crystal novelty of the invention having a cylindrical neck portion 2 terminating in an offset annular screw threaded portion shown at 3. The screw threads on the offset annular portion 3 are molded thereon to receive a screw threaded closure cap 4 adapted to secure the disc-like member 5 in position against the peripheral edge of the annular portion 3. The disc-like member 5 has an annular recess 6 formed therein for receiving the ring-like gasket 7 which is pressed in intimate contact against the peripheral edge of the annular portion 3 for establishing a vacuum-tight seal. The screw threads 3a on the skirt of the closure cap 4 engage the screw threads 3a on the exterior of the annular portion 3 for insuring a tight closure between the closure cap 4 and the neck of the container 1. The annular instruck portion 4b of closure cap 4 bears directly against the disc-like member 5 for forcing the gasket 7 which is carried by disc-like member 5 into sealing relation with the peripheral edge of the annular screw threaded portion 3.

The interior annular wall of the cylindrical neck portion 2 is provided with pockets or recesses at 8 and 9 therein. These pockets or recesses are formed in the interior wall of the cylindrical neck 2 during the blowing and molding of the container. While I have shown but two diametrically opposed pockets or recesses 8 and 9, it will be realized that a multiplicity of pockets or recesses may be provided and distributed around the interior wall of the cylindrical neck portion 2 in order to insure proper support and spacing for the ornamental figure.

I have represented the container by reference character 1 which may have the interior wall of the cylindrical neck thereof shaped on a corrugated taper at 28, thus providing a frusto-conical interior surface having alternate peaks and valleys. The pockets or recesses 8 and 9 are formed as heretofore explained in the interior of the annular screw threaded portion 3 to receive the bar-like lugs 14 and 15 which project from the base of the figure represented generally at 10.

The interior wall of the cylindrical neck portion 2 is frusto-conical as shown at 28 and correspondingly the base of the ornamental figure 10 is frusto-conical shaped. The frusto-conical base of the ornamental figure 10 is provided with a smooth surface 29 as more clearly shown in Fig. 6. The base 29 includes transversely extending passages 27 therein through which the fluid and suspended precipitate are free to circulate. Substantially rigid support may be imparted to the figure 10 by the contacting rela-

tion between the tapered flutings or corrugations 28 in the neck portion 2 and the smooth walled tapered base 29 while leaving the passages 26 between the flutings 28 open for the circulation of the fluid and precipitate. Thus the fluid and precipitate may freely move from the main body of the liquid along the passages 26 and diametrically across the passages 27 for including a whirling movement in the fluid body.

The precipitate which is floatingly suspended in the liquid within the container is whirled through the liquid by the circulatory currents through the passages 27 and along the passages 26 between the flutings 28 and around the ornamental figure as a result of shaking or agitation of the figure as it is lifted from its position as a paperweight. The peaks of the corrugations on the interior frusto-conical shaped wall of the neck 2 of the container establish surface contact with the smooth frusto-conical shaped wall 29 of the ornamental figure 10 securely positioning the figure in position while providing for the free circulation of the fluid between the valleys of the flutings 28 and the passages 27 in the base of the figure.

The assembled crystal novelty and paperweight is mounted on a suitable base which I have represented by the vitreous molding 30 having a central recess 31 for receiving the downwardly projecting capped end of the container 1. After the capped end of the container 1 is inserted in the recess 31, a suitable cement is filled into the base for securing the figure in position as shown at 32.

I have shown but one method of securing the closure cap 4 to the neck of the container 1, that is, through screw threads 3a but it will be understood that the seal may be established in other ways, that is, by a crimped cap or friction or positive closure device and my invention is not limited to the screw threaded closure.

While I have described my invention in certain of its preferred embodiments, I realize that modifications may be made and that other forms of construction embodying my invention may be employed and I desire that it be understood that no limitations upon my invention are intended other than may be embodied by the scope of the appended claims.

What I claim as new and desire to secure by Letters Patent of the United States is as follows:

1. A crystal novelty comprising, a fluid container having an annular neck portion at one side thereof, the interior wall of said neck portion being inclined inwardly toward the interior of said container and having longitudinally disposed peaked corrugations thereon and having diametrically opposite pockets formed therein, a figure insertable through said neck portion, said figure having a substantially frusto-conical base portion adapted to contact with and be supported by the peaked corrugations on the inwardly inclined interior wall of said neck portion, diametrically opposite lugs extending from said base portion and engageable in the pockets in said neck portion for maintaining the said figure in a vertically erect position in said fluid container, the frusto-conical base portion of said figure being apertured for the circulation of fluid through said figure and around said container, and means engageable with the exterior of said neck portion and said base for securing said figure in position within said container.

2. A crystal novelty comprising, a fluid contain-

er having a neck portion at one side thereof, the interior walls of said neck portion being corrugated in section and substantially frusto-conical in shape and having diametrically opposite pockets formed therein, a figure insertable through said neck portion, said figure having a substantially frusto-conical shaped base adapted to contact with peaks of the corrugations of the interior walls of said neck portion, and lugs extending from said base and engageable in the pockets in said neck portion, and means engageable with the exterior of said neck portion for maintaining said base in position within said fluid container.

3. A crystal novelty comprising, a fluid container having a neck portion at one side thereof, the interior walls of said neck portion being corrugated in section and substantially frusto-conical in shape and having diametrically opposite pockets formed therein, a figure insertable through said neck portion, said figure having a substantially frusto-conical shaped base adapted

to contact with peaks of the corrugations of the interior walls of said neck portion, lugs extending from said base and engageable in the pockets in said neck portion, circulatory passages extending through said base and connected through the channelways between said corrugations for the circulation of fluid beneath said figure, and means engageable with the exterior of said neck portion for maintaining said figure in position within said fluid container.
